UNITED STATES PATENT OFFICE.

LEWIS JOEL BENNETT, OF MEMPHIS, TENNESSEE, ASSIGNOR OF ONE-THIRD TO GERSON SCHARFF AND ONE-THIRD TO DWIGHT M. ARMSTRONG, BOTH OF MEMPHIS, TENNESSEE.

MATTRESS AND METHOD OF MAKING SAME.

1,355,730.

Specification of Letters Patent. Patented Oct. 12, 1920.

Application filed March 6, 1920. Serial No. 363,631.

To all whom it may concern:

Be it known that I, LEWIS JOEL BENNETT, a citizen of the United States, residing at Memphis, in the county of Shelby and State of Tennessee, have invented certain new and useful Improvements in Mattresses and Methods of Making Same, of which the following is a specification.

This application is a continuation of and 10 substitute for application No. 314,288, filed July 30, 1919, and the invention relates to mattresses and the methods of making the same, and has for an object to provide an improved mattress made by an improved 15 method whereby the boxing about the edge of the mattress is made as a separate structure and applied to the mattress independently of the cover.

Further objects of the invention is to provide 20 a mattress wherein the edge ordinarily referred to as the boxing is constructed and stuffed separately from the mattress and is applied by sewing to the top and bottom of the mattress whereby the top and bottom 25 may be removed independently of the boxing, or the boxing may be removed independently of the top and bottom as necessity of renovation may require.

With these and other objects in view the 30 device comprises certain novel combinations and arrangements of parts and steps of method as will be hereinafter more fully described and claimed.

Referring to the accompanying drawings 35 which are made a part hereof, and on which similar reference characters indicate similar parts.

Figure 1 is a transverse sectional view 40 through the boxing of the mattress.

Fig. 2, a perspective view of an indeterminate length of the boxing before being applied to the mattress, and

Fig. 3 is a plan view of a fragment of a 45 mattress with the boxing applied.

In making a mattress in accordance with the method of the present invention a strip of material of indeterminate length indicated at 1 and of a width corresponding to the thickness of the required mattress plus 50 the turned over edge portions 2 is used as a base. To this base portion 1 the cover member 3 is secured by stitching 4 inserted through the turned edges 2 and with the stuffing material 5 inserted between the 55 cover member 3 and the strip 1. The stuffing

within the cover may be inserted in any approved manner, before or after the cover member 3 has been applied, and is manipulated in any approved manner so that the stitches are inserted adjacent the edges of 60 the strip 1 and form rolls 7, to produce the ordinary and desired rolled edge found in the usual mattress.

For the purpose of compacting the stuffing 65 5 and stiffening the box structure stitching 8 is employed in any approved manner as in the form of "quilting" as shown more particularly at Fig. 2. The cover member 3 in addition to having sufficient width to inclose the stuffing and produce the edge roll 8 is 70 also of sufficient width to produce the strips 9 extending the entire length of such boxing structure. The boxing structure so constructed is a complete structure in itself and may be made in any desired length or 75 indeterminate lengths and severed into proper lengths for use. In whatever manner the boxing structure is made it is attached to the top and bottom fabric 10 by means of stitches 11 extending entirely around the top or 80 bottom and the major portion of the distance around the other member leaving an opening indicated at 12 in Fig. 3 for inserting the mattress stuffing 13, also shown in that figure. In turning the boxing strip about 85 the corners of the top and bottom 10 folds or gathers 14 are formed. After sewing up the opening 12 the mattress is tufted in the usual manner as indicated at 15.

While forming no part of the patentable 90 features of the present invention the boxing strip as disclosed at Fig. 2 will be constructed on a sewing machine especially adapted for the purpose, whereby the entire boxing strip will be sewed simultaneously 95 and can therefore be constructed by anyone competent to run an ordinary sewing machine. It is also sewed to the top and bottom 10 by anyone who can run a sewing machine and after being so sewed is turned through 100 the opening 12 before being stuffed.

Having thus fully described my said invention, what I claim as new and desire to secure by Letters Patent, is:

1. The method of making a mattress consisting in producing a boxing including spaced edge rolls and sewing the boxing so constructed to the top and bottom fabric of the mattress.

2. The method of making a mattress con- 110

- sisting in making a boxing of spaced stuffed fabrics having spaced free edges and securing the free edges to the border of the top and bottom of a mattress fabric, respectively. 5
6. 3. The method of making a mattress consisting in employing a strip of base material, a strip of material wider than the base strip with stuffing introduced between the strips, stitching through the strips to produce corner rolls and attaching the structure so formed to the border edges of the top and bottom fabric of a mattress. 10
7. 4. The method of making a mattress consisting in employing a strip of base material, a second strip of material wider than the base strip and extending at both edges beyond the base strip, introducing stuffing between the strips, sewing through the strips to produce corner rolls, and attaching the extended edges to the border edges of the top and bottom fabric of a mattress. 15
8. 5. The method of making a mattress consisting in employing a strip of base material, a strip of material secured to the base strip and wider than said base strip extending beyond the base strip at both edges, stitching through the stuffing and both strips extending the edges over the edges of the top and bottom fabrics of a mattress and securing the extended edges to such top and bottom fabrics. 20
9. 6. The method of making a mattress consisting in employing a base strip, a second strip secured to the base strip and presenting fullness as compared to the base strip between the securing lines and extending beyond the edges of the base strip, introducing stuffing between the strips, employing part of the fullness of the second strip to produce a corner roll embracing a part of the stuffing, and securing the boxing so formed to the border edges of the top and bottom fabric of a mattress. 25
10. 7. The method of making a mattress in employing a base strip, a second strip sufficiently wider than the base strip to extend upon its opposite edges, introducing stuffing material into the fullness of the second mentioned strip, gathering a portion of the stuffing material into a roll at one side of the strip, stitching through the two strips to complete the roll and inclose the stuffing material, stitching through the two strips and the stuffing material for stiffening the structure, and stitching the extended edges of the strip to the border edges of the top and bottom fabric of a mattress. 30
11. 8. The method of making a mattress consisting in employing a base strip, a second strip sufficiently wider than the base strip so that when stitched thereto by stitching parallel with the edges of both strips the edges of the second strip extend beyond the edges of the base strip and produce a full- ness between the stitchings, introducing 65 stuffing into the fullness between the strips, gathering a part of the fullness to produce a corner roll, stitching through both strips adjacent the first mentioned stitching to complete the roll and inclose the stuffing 70 therein, stitching other rows of stitching through both strips and the stuffing other than the corner roll and securing the extended edges of the top and bottom fabric of a mattress. 75
12. 9. The step in the method of making a mattress consisting in producing a roll edge boxing independently of and adapted to be attached to a mattress. 80
13. 10. The step in the method of making a mattress consisting in producing an indeterminate length of roll edge boxing proportioned to be secured about the edge of a mattress. 85
14. 11. The step in the method of making a mattress consisting in producing a roll edge boxing having inner and outer fabric strips with stuffing material interposed between and adapted to be secured as an organization to a mattress. 90
15. 12. A mattress comprising top and bottom fabric members, stuffing introduced between the top and bottom fabric members, and a boxing extending about the edges of the stuffing and having free edges extending a limited distance inwardly upon the top and bottom and attached to the edges of the top and bottom fabric, respectively. 95
16. 13. A mattress comprising stuffing material, top and bottom fabrics embracing the stuffing material and smaller in all dimensions than the required dimensions of the mattress, and a boxing member extending about the sides of the stuffing material and over the top and bottom thereof and connected to the top and bottom fabrics. 100
17. 14. A mattress comprising stuffing material, top and bottom fabrics embracing the stuffing material, and a boxing member secured about and to the edges of the top and bottom fabrics and embodying spaced fabric strips and corner rolls with independent bodies of stuffing therein. 105
18. 15. A roll edge boxing for a tufted mattress comprising a tube having filling and edge extensions, the latter being adapted to be stitched to the mattress fabric in overlapping relation with tufted portions of the mattress and secured to the latter by the tufting thereof. 110
19. In witness whereof I have hereunto set my hand and seal at Memphis, Tennessee, this 16th day of February, A. D. nineteen hundred and twenty. 115
